CLAIM

The ornamental design for a combination syringe-shaped container and lip balm, as shown and described.

DESCRIPTION

FIG. 1 is a front perspective view of the combination syringe-shaped container and lip balm;

FIG. 2 is a front side view thereof;

FIG. 3 is a rear side view thereof;

FIG. 4 is a left side view of the combination syringe-shaped container and lip balm, the right, top, and bottom side views being identical to the left side view;

FIG. 5 is an additional front perspective view thereof;

FIG. 6 is an exploded perspective view thereof;

FIG. 7 is a rear perspective view thereof;

FIG. 8 is an exploded rear perspective view thereof;

FIG. 9 is a cross-sectional view thereof of the portion shown in FIG. 5; and,

FIG. 10 is a cross-sectional view thereof of the portion shown in FIG. 4.
